UNITED STATES PATENT OFFICE.

ALBERT H. LAGE, OF PAULLINA, IOWA.

COMBINATION TRESTLE AND SCAFFOLD-SUPPORT.

1,261,560.

Specification of Letters Patent.

Patented Apr. 2, 1918.

Application filed June 20, 1917. Serial No. 175,887.

To all whom it may concern:

Be it known that I, ALBERT H. LAGE, a citizen of the United States, residing at Paullina, in the county of O'Brien and State 5 of Iowa, have invented new and useful Improvements in Combination Trestles and Scaffold-Supports, of which the following is a specification.

This invention relates to improvements in 10 carpenters' trestles.

The principal objects of the invention are to provide a carpenter's trestle or horse which will be readily collapsible to facilitate carrying it from place to place, and which 15 may be adapted to constitute an efficient scaffold support or bracket when desired.

Other objects are to simplify the construction of the device, and to combine therein the features of lightness and strength.

20 To effect the above ends, I have embodied the invention in the novel constructional features and arrangement and disposition of the same as hereinafter described, set forth in the claims, and illustrated in the 25 drawings.

In the drawings:

Figure 1 is a side elevation showing the device as arranged for use as a trestle.

Fig. 2 is an end view of the same.

30 Fig. 3 illustrates one method of using the device as a scaffold support the legs not being shown.

Fig. 4 shows an application of the device whereby the scaffold boards are sustained 35 without the use of auxiliary supporting devices.

The trestle has the usual top bar designated in the drawings by the numeral 1, and preferably consisting of channel iron 40 having walls 2 united by a web 3. The bar 1 has at one end spaced ears 4 here shown as formed by cutting away the web 3, and at the other end a lug 5 formed by removing portions of the walls 2, and the ears 4

45 and lug 5 are formed with openings 6' for receiving nails or other securing means. Swingly attached near each end of the bar 1 is a pair of pivotally connected legs 6 adapted to be spread apart or to be brought 50 together and stored within the channel bar 1. In the present instance the legs are of angle iron, connected to the bar 1 by bolts 8 inserted in openings 9 provided in the walls

2 of the bar and the legs 6, the openings 9 in the legs 6 being slightly elongated to permit the legs to move to a parallel position. The walls 2 are formed adjacent the openings with notches 10 for receiving the legs when spread apart to prevent movement relatively to the bar. To retain the legs in such position 55 a leg of each pair has pivotally attached, at a convenient point one end 11 of a cross-brace 12 carrying near the other end 13 a notch for engagement with a stud 14 provided on the other leg 6 of the particular 60 pair. One of the legs 6 is further provided at the lower end with a pivotally attached bar 15 bent at the free end to constitute a hook 16; and a stud 17 projects from the other leg of the same pair in a position to 65 prevent outward movement of the hook 16 beyond a desired point in the parallel position of the legs 6.

In practice for use as a scaffold support the legs 6 may be disposed in the collapsed 70 position, and the lug 5 secured by nails or other suitable means on a horizontally disposed block attached to a building; and any convenient piece of timber may be inserted between the ears 4 and similarly secured to 75 support the outer end of the bar 1. When desired, the bar 1 may be placed in a vertical position and the upper pair of legs extended horizontally in parallelism for engagement of the hook 16 with a studding or 80 other convenient part of a building, and a block attached to the studding to support the leg 6 carrying the hook if necessary. In this instance, the other pair of legs is preferably spaced apart with the notch in cross 85 bar 12 in engagement with stud 14 and placed against the wall of the building to 90 steady the scaffold.

The herein described embodiment is not to be interpreted as in any way limiting the 95 invention, as I am aware that many and varied forms may be constructed without departing from the spirit of the invention, and the right is reserved to variation, alteration, and modification within the scope of 100 the claims.

What I claim is:

1. In a device of the class described, a top bar of channel form having a pair of notches in its side members adjacent each end of the 105 bar and bolt holes located above said notches,

- a pair of legs engaging with each pair of notches when in operative position, and a bolt passing through said bolt holes and engaging the upper ends of the legs.
- 5 2. A device of the class described comprising a top bar, a pair of legs pivotally connected thereto adjacent each end thereof, a

brace rod detachably connecting the legs together to hold them in extended position, and a hook pivoted to the lower end of one leg and adapted to engage a beam for holding the top bar in vertical position.

In testimony whereof I affix my signature.

ALBERT H. LAGE.
